(57) **CLAIM**

The ornamental design for a swimsuit, as shown and described.

DESCRIPTION

FIG. 1 is a front perspective view of a swimsuit, showing my new design;

FIG. 2 is a rear perspective view thereof;

FIG. 3 is a front view thereof;

FIG. 4 is a rear view thereof;

FIG. 5 is a left side view thereof; and,

FIG. 6 is a right side view thereof.

The broken line showing of swimsuit is for the purpose of depicting environmental structure and forms no part of the claimed design.
